Primary Examiner — Lucy Lieberman(74) *Attorney, Agent, or Firm* — Polster Lieder Woodruff & Lucchesi, L.C.(57) **CLAIM**

The ornamental design for an inflatable cushion insert, as shown and described.

DESCRIPTION

FIG. 1 is a top, front and side perspective view of an inflatable cushion insert showing my new design;

FIG. 2 is top plan view of FIG. 1;

FIG. 3 is a bottom plan view of FIG. 1;

FIG. 4 is a front elevational view of FIG. 1;

FIG. 5 is a rear elevational view of FIG. 1;

FIG. 6 is the right side elevational view of FIG. 1;

FIG. 7 is the left side elevational view of FIG. 1;

FIG. 8 is a top, front and side perspective view of the inflatable cushion insert in a foam base to illustrate environment;

FIG. 9 is a top plan view of FIG. 8;

FIG. 10 is a front elevational view of FIG. 8;

FIG. 11 is a rear elevational view of FIG. 8;

FIG. 12 is a right side elevational view of FIG. 8; and,

FIG. 13 is a left side elevational view of FIG. 8.

The inflatable cushion insert is shown with the front and side flaps folded into a different position in FIG. 8.
